UNITED STATES PATENT OFFICE

RALPH COPP, OF ST. LOUIS, MISSOURI, ASSIGNOR TO PEVELY DAIRY COMPANY, OF ST. LOUIS, MISSOURI, A CORPORATION OF MISSOURI

LIQUID COOLER

Application filed November 2, 1931. Serial No. 572,595.

This invention relates to liquid coolers.

An object of this invention is to provide a device for cooling liquids comprising a series of parallel vertical pipes opening at their upper and lower ends into horizontal header pipes containing a refrigerant, in combination with means for spreading a flow of liquid over said pipes so that the liquid will flow by gravity along said pipes, and in combination with a tank enclosing the cooling unit arranged in such a manner that effective cooling will occur whether the withdrawal be constant and directly after the liquid has flowed over the pipes, or whether the tank be used as a storage reservoir and the liquid be withdrawn as required.

Another object of the invention is to provide a device of the character described including a tank enclosing the refrigerating unit which will be effective regardless of the level of the liquid in the tank or the rate of discharge therefrom.

Other objects will appear from the following description, reference being made to the accompanying drawings, in which—

Fig. 1 is a side elevation of my improved cooler with the wall of the enclosing tank partly broken away.

Fig. 2 is a vertical section of the upper portion of the cooler approximately on the line 2—2, Fig. 3.

Fig. 3 is a side elevation of the upper portion of the cooler shown in Fig. 2.

Fig. 4 is a detail partly in section of a float controlled valve included in the invention.

The refrigerating unit of the cooler is mounted in a tank 1, which may be supported by upright members 2, and may be supported inside the tank by hangers 3. The upper header, to which the hangers 3 are secured, comprises a horizontal pipe 4 and the lower header comprises a horizontal pipe 5. These horizontal pipes 4 and 5 are connected by a longitudinal series of vertical pipes 6, the upper ends of which open into the pipe 4 and the lower ends of which open into the pipe 5. The pipes 6 are of less diameter than the pipes 4 and 5.

The pipe 4 has communication, through a pipe section 7, with a liquid chamber 8, from

the lower end of which a pipe 9 opens into a circulating pump 10 having communication with the adjacent pipe 5 through a pipe connection 11. From the upper end of the chamber 8 a pipe 12 extends to an absorber or compressor (not shown) and is equipped with a back pressure valve device 13, of any known or appropriate construction, which acts to hold a constant pressure and thereby maintain approximately a constant temperature in the refrigerating unit, but does not prevent passage of the gasified refrigerant therethrough when the pressure in the cooler exceeds the predetermined amount of pressure.

A return pipe 14 for the condensed refrigerant has communication through a pipe 15 with the pipe 9 by either of two paths, through a float controlled valve 16 and a pipe 17, controlled by a manually operable valve 18, or through a pipe 19 controlled by a manually operable valve 20.

The valve 16 is operated by a link 21 pivotally connected to a lever 22, to which is secured a float 23 by an arm 24. Thus, when the valve 20 in the pipe 19 is closed and the valve 18 in the pipe 17 is open, the float operated valve 16 will be effective to automatically maintain a constant level A of liquid refrigerant as illustrated in Fig. 4 and as shown by dotted line Fig. 1. If manual operation is desired the valve 18 is closed and the level of liquid regulated manually by the valve 20. It is to be understood, however, that the circulating pump 10 is effective to maintain the refrigerant in the vertical pipes 6 to the top thereof.

A distributing device comprises a pipe 25, supported by the hangers 3 and having through its lower side numerous outlet openings 26. These openings 26 constitute a longitudinal series of openings immediately above the pipe 4 so that any liquid discharged through the openings 26 is discharged upon the upper portion of the pipe 4. A portion of this liquid passes directly from the surface of the pipe 4 to the vertical pipes 6. The remaining portion of this liquid passes from the surface of the pipe 4 to distributor strips 27, located between and connecting with the upper ends of the pipes 6 and also connect-

ing with the lower side of the pipe 4 and having on their opposite side downwardly diverging grooves 28. That portion of the liquid flowing from the pipe 4 to the distributor strips 27 is conducted by the grooves 28 to the respective pipes 6 so that all of the liquid is caused to flow downwardly along the pipes 6 and is thereby subject to the cooling action of the refrigerant.

10 A supply pipe 29 opens into a pipe 30, supported longitudinally within the pipe 25 and spaced therefrom. The pipe 30 is concentric with the pipe 24 and has therethrough a longitudinal series of holes 31 from which the 15 liquid is discharged into the pipe 24.

The tank has an outlet 32 controlled by manually operable valve 33. The tank also has manholes 34 and covers 35 for convenience in construction, cleaning and repairing.

20 An agitator is provided for use when the level of the liquid to be cooled is permitted to rise in the tank 1. This agitator comprises a series of vanes 36 secured to a shaft 37 which may be rotated by a motor 38.

25 In operation the liquid to be cooled is admitted to the pipe 30 from the pipe 29. From the pipe 30 the liquid to be cooled passes through the openings 31 of the pipe 25 and thence through the openings 26 to the upper 30 surface of the pipe 4 approximately throughout the length of said pipe 4. The liquid flows downwardly across the opposite sides of the pipe 4, a portion of the liquid passing directly to the vertical pipes 6 and the remainder of the liquid passing to the distributor strips 27 and being conducted along the grooves 28 to the respective pipes 6. Thus the entire amount of liquid is caused to flow along the pipe 6 and across the lower pipe 5 whence it drops to the bottom of the tank 1 and will be directly removed through the pipe 32 when the valve 33 is open.

If, however, it is desired to use the tank 1 as a storage reservoir the level of the liquid to be cooled will rise in the tank 1. In such a case the cooling surface to which the liquid will be directly exposed will be reduced. By operating the agitator 36 the liquid in the tank 1 will be circulated and thus compensation will be made for the reduction in the cooling surface directly exposed to the liquid in its downward travel along the pipes 6. It will be seen, therefore, that substantially the same cooling effect will be obtained whether liquid is withdrawn directly from the tank after it has been passed over the pipes 6 or whether the liquid is allowed to accumulate to a relatively high level in the tank.

60 Parts of the invention may be used without the whole and various changes may be made in the details of construction, within the scope of the appended claims, without departing from the spirit of this invention.

I claim:

65 1. A cooler adapted to contain a volatile

refrigerating liquid and having a series of vertical pipes, a horizontal pipe opening into the upper ends of the vertical pipes, a horizontal pipe opening into the lower ends of the vertical pipes, a chamber communicating at its top with the first mentioned horizontal pipe and at its bottom through a conduit with the second mentioned horizontal pipe, a valve operated automatically by a float in said chamber and adapted to maintain in the chamber a level of liquid below the first mentioned horizontal pipe, and a circulating pump located in said conduit and adapted to maintain liquid in the vertical pipes to the top thereof.

2. A cooler adapted to contain a volatile liquid refrigerant and having a top header, a bottom header, conduits intermediate said headers presenting a relatively large outer surface, a chamber communicating at its top with the top header and at its bottom through a conduit with the bottom header, a valve operated automatically by a float in said chamber and adapted to maintain in the chamber a level of liquid below the top header, and a circulating pump located in said conduit and adapted to maintain liquid in said intermediate conduits to the top thereof.

3. A cooler adapted to contain a volatile liquid refrigerant and having a top header, a bottom header, conduits intermediate said headers presenting a relatively large outer surface, a chamber communicating at its top with the top header and at its bottom through a conduit with the bottom header, a valve operating automatically by a float in said chamber and adapted to maintain in the chamber a level of liquid below the top header, a circulating pump located in said conduit and adapted to maintain liquid in said intermediate conduits to the top thereof, a conduit connected to said chamber above the level of liquid to be maintained therein, and a back pressure valve in said last named conduit adapted to maintain a substantially constant pressure in the cooler.

4. A cooler of the character described including a tank, a valved drain in the tank, means for agitating liquid in the tank, and a refrigerating unit adapted to contain a fluid refrigerant and having a series of vertical pipes, a horizontal pipe opening into the upper ends of said vertical pipes, means for discharging liquid along the upper side of said horizontal pipe, and means for preventing the liquid from dripping from said horizontal pipe and causing the liquid to flow downwardly along said vertical pipes.

5. A cooler of the character described comprising a tank, a valved drain in the bottom of the tank, an agitator in the tank, and a refrigerating unit adapted to contain a fluid refrigerant and having a series of vertical pipes, a horizontal pipe opening into the up-

per ends of said vertical pipes, a horizontal pipe opening into the lower ends of said vertical pipes, means for discharging a liquid to be cooled along the upper side of said horizontal pipe, and means for preventing the liquid from dripping from the first mentioned horizontal pipe and causing the liquid to flow downwardly along said vertical pipes.

5 6. A cooler of the character described including a tank, a valved drain in the tank, an agitator in the tank, a refrigerating unit in said tank adapted to contain a fluid refrigerant and having a vertical exterior surface, means for causing all of the liquid to be cooled to flow upon said surface, and mechanism other than said agitator for forcing circulation of the fluid refrigerant through said refrigerating unit.
